SUPPORT ARRANGEMENT FOR X-RAY
FILMING EQUIPMENT

José Jany, São Paulo, Brazil

Application June 17, 1942, Serial No. 447,361

3 Claims. (Cl. 250—65)

The present invention relates to a support arrangement for an X-ray tube and X-ray filming equipment.

One object of the invention is to provide supports for the X-ray tube and for the photographic equipment which permit various adjustments of the supported elements in such a manner that their focal axes remain always in a predetermined vertical plane.

Another object of the invention is to provide supports which can be easily transported to various points in a room while retaining the focal axis of each piece of equipment in a predetermined vertical plane.

A still further object of the invention is to provide an arrangement in which the support for the X-ray tube and that for the photographic equipment are displaceable relative to each other along parallel tracks, the X-ray tube and the photographic equipment being adjustably carried by their respective supports so as to have their focal axes always disposed in one and the same vertical plane parallel to and between the support tracks.

Still another object of the invention is to provide, in combination with a support arrangement in which the support for the X-ray tube and that for the photographic equipment are displaceable along parallel tracks, as described, an X-ray table displaceable along a third track extending parallel to and between said first two tracks, and capable of being inserted between the X-ray tube and the photographic equipment.

My prior U. S. Patent 2,205,853 described photographic equipment suitable for the filming of X-ray images and the photographic equipment referred to in the present specification may be of this type, but it will be understood that other photographic equipment capable of serving the same purpose may be substituted.

The principal features of my invention are set forth in the following description, defined in the appended claims and illustratively exemplified in the accompanying drawings, in which

Fig. 1 is a side view of a support standard according to the invention carrying photographic equipment substantially as described in my prior U. S. Patent 2,205,853;

Fig. 1A is a left hand end view of Fig. 1;

Fig. 1B is a top view of Fig. 1;

Fig. 1C is a side view similar to that of Fig. 1 with the photographic equipment adjusted to a different position;

Fig. 2 is a side view of a support arrangement according to the invention comprising, in addi-

tion to the support for the photographic equipment, a similar support for the X-ray tube and an X-ray table, the latter being in an inoperative position at the right hand side of the figure;

Fig. 2A is a top view of the arrangement according to Fig. 2;

Fig. 3 is a side view similar to that of Fig. 2 in which the X-ray tube and photographic equipment are adjusted to an inclined working position and the X-ray table is placed, in a similarly inclined position, between the X-ray tube and the photographic equipment, and

Fig. 3A is a top view of the arrangement according to Fig. 3.

Referring now to the drawings, and particularly to Figs. 1 to 1B, a support according to the invention comprises a hollow tubular standard 1 mounted on a base plate 4 provided with casters to be displaceable along a pair of rails 5. A sleeve 2 is vertically slidable on the standard 1 and includes as an integral part thereof a hollow arm projecting at right angles to the standard 1 and to the rails 5. A horizontal rod 3 has one end thereof rotatably inserted into and carried by said hollow arm while on the other end of the rod 3 in a vertical plane parallel to and on one side of the rails 5, there is mounted the photographic equipment. The photographic equipment includes, for instance, two pairs of telescoping tubes 6, the outer tube of each pair being secured to the rod 3, a frame 7 carrying a luminous screen, an extension bellows 8, a casing 9 for the cinematographic or other photographic camera, a support 10 for said casing secured to the right hand ends of the telescoping tubes 6 and an electromagnetic switch 11 for operating the camera in the casing 10.

The weight of the sleeve 2, arm 3, photographic equipment 6-11 and of the camera is counterbalanced by a weight (not shown) which is slidable within the standard 1 and connected with the sleeve 2 by means of a chain 12.

In Figs. 1, 1A and 1B, the horizontal rod 3 is adjusted to a position in which the telescoping tubes 6 and the bellows 8 of the photographic equipment extend in a substantially horizontal direction, while in Fig. 1C, the rod 3 has been turned through 90° about its own axis in the hollow arm of sleeve 2, to bring the tubes 6 and bellows 8 of the photographic equipment into the vertical position shown.

Figs. 2 and 2A show an arrangement including, in addition to the support elements 1-5 for the photographic equipment 6-11, a second similar standard 13 with a sliding sleeve 15 con-

nected by means of a chain 14 to a counterweight (not shown) which slides inside of the standard 13. A rod 17, rotatable in a hollow arm integral with the sleeve 15, carries the X-ray tube 18 and two telescoping members 16 adapted to be connected with their ends to the frame 7 of the photographic equipment (see Fig. 2A). The standard 13 is erected on a base plate 19 provided with coasters to run on a pair of rails 20 extending parallel to and at a distance from the pair of rails 5. The hollow arm and horizontal rod 3 project from the standard 1 at right angles to the rails 5 and towards the rails 20 and the hollow arm and horizontal rod 17 project from the standard 13 at right angles to the rails 20 and toward the rails 5, the photographic equipment 6-11 and the X-ray tube 18 being mounted on the rods 3 and 17, respectively, in such a manner that their focal axes are disposed invariably in one and the same vertical plane intermediate the rails 5 and the rails 20.

An X-ray table shown on the right hand side of Figs. 2 and 2A comprises a base 21 and a tiltable top 22 and is slidable on a pair of rails 28 extending parallel to and between the rail pairs 5 and 20, the longitudinal center line of the table top 22 being disposed in the same vertical plane as the focal axes of the X-ray tube 18 and of the photographic equipment 6 to 11.

A control mechanism for the standard 13 carrying the X-ray tube 18 includes an endless cable 24 secured to the base plate 19 (see Fig. 2) and running over two fixed pulleys 23 and 25, the latter being rotatable over a third pulley 26 by means of a crank 27.

In Figs. 2 and 2A the X-ray tube 18 and the photographic equipment 6-11 are adjusted to positions in which their focal axes extend in a substantially horizontal plane, and the X-ray table 21, 22 is in its inoperative position at the right hand end of the rails 28.

According to Figs. 3 and 3A, the sleeve 2 on standard 1 is shifted to a higher level and the sleeve 15 on standard 13 to a lower level, while the two horizontal rods 3 and 17 are turned in their hollow support arms to angular positions in which the focal axes of the X-ray tube 18 and of the photographic equipment 6-11 are disposed in a common inclined plane. The X-ray table 21, 22 is shifted to a position between the rods 3 and 17 and the table top 22 is tilted to extend

between the X-ray tube 18 and the frame 7 at substantially right angles to the inclined focal plane.

It will be seen that in the arrangement set forth each element, X-ray tube, photographic equipment and X-ray table, can be used separately and independently or in combination with any one or all of the other elements. Whenever a combination of two or more elements is to be effected, the desired elements are shifted along their rails into the proper positions without any lateral adjustment because the focal axes of the X-ray tube and of the photographic equipment are invariably disposed in a common vertical plane with the longitudinal center line of the X-ray table top so that only the mutual distances, the height and the angular inclination of the elements need be adjusted. These adjustments can be easily and accurately effected owing to the construction of the support standards set forth.

I claim:

1. A support arrangement for an X-ray tube and film-photographic equipment to cooperate with said X-ray tube, comprising two pairs of rails arranged parallel to and at a distance from each other, two base plates having coasters to run on said two pairs of rails, respectively, a standard erected on each of said base plates, means adjustable on and projecting from one of said standards to support an X-ray tube with its focal axis in a predetermined vertical plane extending parallel to and between said two pairs of rails, and means adjustable on and projecting from the other standard to support a photographic equipment with its focal axis in said same predetermined plane.

2. A support arrangement, as claimed in claim 1, in which said means for supporting the X-ray tube includes two telescoping members extending in vertical planes parallel to and equidistant from said predetermined plane, said telescoping members being adapted to be connected to the photographic equipment to fix the relative positions of said X-ray tube and photographic equipment.

3. A support arrangement, as claimed in claim 1, including a third pair of rails extending parallel to and between said first two pairs of rails, and an adjustable X-ray table supported on and displaceable along said third pair of rails.

JOSÉ JANY.
